UNITED STATES PATENT OFFICE.

EDWIN L. WIEGAND, OF DORMONT BOROUGH, PENNSYLVANIA.

ELECTRICAL HEATING DEVICE.

Application filed February 1, 1923. Serial No. 616,445.

This invention relates to improvements in electrical heating units of the conduction type wherein the resistor element is entirely encased or embedded in a mass of suitable material of a monolithic nature that is bound by adhesion within a comparatively shallow depression or recess of a suitable metal base or receptacle into which it is pressed during the process of manufacture.

In connection with electrical heating units of the foregoing nature, as constructed prior to my present improvements, considerable difficulty has arisen from the embedding material cracking, or loosening from the walls and surface of the recess of the base, due to the difference in the respective coefficients of expansion of the base and embedding material, or to shrinkage of the embedding material while being fired, or from use at high temperature. There is no way of always entirely overcoming these inherent differences, so that the solution of the problem lies in so constructing the unit that any relative change in extent of the two constituents is compensated for or nullified, or made ineffective as a cause of deterioration.

To this end my invention has for its object to produce an electrical heating unit of the character set forth wherein the depression or recess of the base is divided into a plurality of relatively small communicating cells—preferably as many as is consistent with commercial practice—as by means of ribs or walls, each cell being defined or enclosed by not less than three ribs or walls arranged at an angle to each other. This has the effect of breaking up the mass of embedding material into many comparatively small connected parts or sections and avoids the large uninterrupted expanse that is present in the earlier constructions. By so apportioning the mass of embedding material into small parts or sections, the relation between each part or section and the surrounding metal parts is so changed as to minimize and render practically null the effects resulting from the difference in the expansion or contraction of the two main constituents of the unit.

Advantages arising from this improved construction, aside from that of eliminating cracking and loosening of the embedding material, are: Protection of the resistor and its insulating sheath against mechanical injury, enhanced mechanical strength, due to

the presence of the ribs; a minimum thickness and weight of the metal base or receptacle; increased efficiency through quicker and more uniform distribution of heat and a more rapid temperature rise with a given rate of energy input; increased facilities for the abstraction of heat energy from the resistor resulting in operation at a lower resistor temperature, prolonging life of same; economy of operation; and the promotion and maintenance during the process of manufacture and the life of the device, of mechanical and thermal unity, that is, an absolute continuity of heat conducting substance between the resistor element, which is the source of heat, and the heat yielding surface of the unit, which is so essential to the effectiveness and durability of a conduction type heating unit.

Broadly, then, the aim of my invention is the production of a highly efficient, substantial and durable electrical heating unit of the embedded type for incorporation in hot plates, stoves and ranges, melting pots, and in other electrically heated appliances, and which will readily withstand the hard service, severe strains and the abuses to which appliances of this character are ordinarily subjected.

An embodiment of the invention is illustrated in the accompanying drawing wherein Fig. 1 is a bottom plan view of an electrical heating unit designed for use in hot plates, stoves, ranges or the like; and Fig. 2 is a section on the line 2—2 of Fig. 1.

Describing the invention by the use of reference numerals, 1 designates the base or receptacle which is flat and smooth on one side, to provide a suitable heating surface or working face, while on the other side it is formed with a comparatively shallow recess that is enclosed by a peripheral flange 2. Extending radially inwardly from the flange 2 to a point slightly beyond the center of the base, is a wall 3; and annular flanges 4 and 5 divide the recess into concentric sections. Extending inwardly from flange 2 and outwardly from flange 4, and in both directions from flange 5, are ribs 6, the ones extending from the opposite sides of the flange 5 being shown as in radial alignment and as staggered with respect to those extending from the flanges 2 and 4. It will be observed that flange 4 is not a complete annulus, but that it has ends spaced from the wall 3 so that the part of the recess en-

closed by the flange 4 communicates with that section between flanges 4 and 5. There is no communication, however, between the sections of the recess that are separated by the flange 5.

The recess contains, to the depth shown in Fig. 2, a suitable embedding material 10 which has been pressed firmly within the recess during the process of manufacture. 10 Binding posts or terminals, designated 11 and 12, have their enlarged inner ends or heads 13 encased within the embedding material enclosed by the flange 4 and a resistor element 14, preferably in the nature of a 15 flat wire or ribbon of suitable metal, has one of its ends connected to the terminal 11 and is led therefrom through the opening between the adjacent end of the flange 4 and the wall 3 and throughout a tortuous course 20 between the flanges 4 and 5 and among the ribs 6 to where it is led in through the space between the opposite end of the flange 4 and the wall 3 to the binding post 12, the resistor element being given a serpentine 25 formation so that it will extend into all corners and be properly distributed throughout the entire area of that section of the recess located inwardly of the flange 5.

Binding posts or terminals 15 and 16 are 30 disposed on opposite sides of that section of the wall 3 which extends between the flanges 2 and 5, and a resistor element 17 of serpentine formation is led from one to the other thereof, throughout the space between 35 the flanges 2 and 5, and among the ribs 6 which sub-divide such space, in the manner shown.

When the unit is properly connected, 40 through a circuit containing a suitable switch, with a source of electric energy, the entire unit may be rendered operative by energizing both resistor elements 14 and 17; or, by cutting out one or the other or by throwing both in series, the heat may be 45 reduced, the inner element 14 effecting a greater and more concentrated heat than the element 17. Consequently, three heats may be realized through the use of the unit.

Now that the invention has been specifically described, its purpose may be more fully appreciated if brief consideration is given to the situation which led to its conception.

Prior to my invention, as has already been 55 pointed out, difficulty was experienced in effecting a proper bond between the electrical insulating heat conducting material in which the resistor is embedded and the surface of the base wherewith said material 60 contacts. Due to the difference in coefficients of expansion of the metal whereof the base is formed and of the embedding material, and notwithstanding the very high pressure employed in compressing the material within 65 the recess or cavity, the embedding material

would break away from the surface of the base throughout enlarged areas and in some cases would shrink away from the peripheral walls of the recess, thus becoming loosened, and if it would not entirely fall away 70 it would create a gap between the mass of embedding material and the base which would greatly impair the life of the unit and materially reduce its thermal efficiency, the latter being the obvious result of the 75 separation between the material and the base.

Through my present invention the foregoing difficulties are entirely overcome and intimate and permanent contact of the embedding material with the base is effected. 80 Two factors contribute to this result: First, the dividing of the embedding material into relatively small sections so that the effect resulting from the difference in coefficients 85 of expansion of the two substances is minimized and therefore of no practical consequence; and second, the binding of the material to the base through the flanges and ribs which are in effect anchorage elements 90 that serve to mechanically secure the embedding material to the body portion of the base.

Having thus described my invention, what I claim is:

1. An electrical heating unit of the character set forth comprising a base having an annular flange enclosing a recess, a wall extending from said flange radially inwardly to substantially the center of the recess, a 100 second annular flange substantially concentric with the former flange, the second flange being interrupted in its circumference and having its ends spaced on opposite sides of the aforesaid wall, ribs extending inwardly from the first mentioned flange, other ribs extending outwardly from the second flange in staggered relation to the former ribs, a body of embedding material occupying the recess, terminals embedded within said material and disposed on opposite sides of the said wall within the space enclosed by the second flange, and a resistor element of serpentine formation extending from one of the terminals through the space between one end of the second flange and the said wall and in a tortuous course throughout the space between the first and second flanges and among the aforesaid ribs and through the space between the other end of said second flange and said wall to the other terminal. 110

2. An electrical heating unit of the character set forth comprising a base having a continuous flange enclosing a recess, a second continuous flange spaced inwardly from the first flange and dividing the recess into an outer portion and an inner portion, a third flange spaced inwardly from the second flange, the third flange being non-continuous and having its ends spaced apart, 120

- ribs extending from certain of said flanges and subdividing the recess, a body of embedding material occupying each portion of the recess, a pair of terminals embedded with-
5 in the material occupying the outer portion of the recess, a resistor element of serpentine shape extending from one of the terminals throughout the outer portion of the recess to the other terminal, a pair of terminals
10 situated within the space enclosed by the third flange, and a resistor element extending from one of the last mentioned terminals throughout the space between the second and third flanges to the other of the
15 last mentioned terminals.
3. An electrical heating unit of the character set forth comprising a base having an annular peripheral flange enclosing a recess, a wall extending radially inwardly
20 from said flange toward the center of the recess, a second annular flange spaced inwardly from the peripheral flange and substantially concentric therewith and dividing the recess into an annular outer portion and
25 a circular inner portion, a third annular flange spaced inwardly from the second flange and concentric therewith, the third flange being interrupted in its circumfer-
ence and having its ends spaced in opposite directions from said radial wall, ribs extending inwardly from the peripheral flange, ribs extending outwardly from the third flange, and ribs extending inwardly and outwardly from the second flange thereby to divide the annular and circular portions of the recess into a plurality of cells, a body of embedding material occupying each portion of the recess, a pair of terminals embedded within the material occupying the outer portion of the recess and situated one on each side of and adjacent to the radial wall, a resistor element of serpentine shape extending from one of the terminals in a tortuous course throughout the outer portion of the recess to the other terminal, a pair of terminals situated one on each side of the radial wall within the space enclosed by the third flange, and a resistor element extending from one of said terminals through the space between the second and third flanges to the other terminal.

In testimony whereof, I hereunto affix my signature.

EDWIN L. WIEGAND.
